(No Model.)

I. N. GROVES.
LIFTING JACK.

No. 432,732.

Patented July 22, 1890.

UNITED STATES PATENT OFFICE.

ISAAC N. GROVES, OF MONTESANO, WASHINGTON.

LIFTING-JACK.

SPECIFICATION forming part of Letters Patent No. 432,732, dated July 22, 1890.

Aplication filed April 21, 1890. Serial No. 348,761. (No model.)

To all whom it may concern:

Be it known that I, ISAAC N. GROVES, a citizen of the United States, residing at Montesano, in the county of Chehalis and State of Washington, have invented a new and useful Lifting-Jack, of which the following is a specification.

The invention relates to improvements in lifting-jacks.

10 The object of the present invention is to provide a simple and inexpensive lifting-jack adapted to be readily used for vehicles and for moving lumber and kindred purposes.

The invention consists in the construction 15 and novel combination and arrangement of parts, which will be hereinafter fully described, illustrated in the accompanying drawings, and particularly pointed out in the claims hereto appended.

20 In the drawings, Figure 1 is a perspective view of the lifting-jack constructed in accordance with this invention. Fig. 2 is a vertical longitudinal sectional view. Fig. 3 is a horizontal sectional view. Fig. 4 is a detail view 25 of the standard.

Referring to the accompanying drawings, 1 designates the standard, which is provided at one side with a recess 2, that extends from its upper end 3 about half the length of the standard, and is adapted to receive a vertical movable jack-bar 4. The jack-bar 4 is rounded at 5 and conforms to the configuration of the recessed portion 2 of the standard and is adapted when in its lowest position to form a 30 continuation of the standard and have its faces flush with the faces of the standard. The standard is provided with a longitudinal groove 6 and a slot 7, which communicates with the groove, that extends longitudinally 35 along the recessed portion 2 and is adapted to receive a rack-bar 8, which is seated in a similar groove 9 of the jack-bar and is provided at its upper end with a point 10 and at its lower end with a perforation 11, through which 40 passes a screw or similar means for securing the rack-bar to the jack-bar. The jack-bar is maintained at any desired elevation by a spring-actuated pawl 12, which is T-shaped and is arranged in a slot or hole 13, and has 45 coiled upon it a spiral spring 14, that engages a shoulder 15 in the slot or hole 13 and the cross-bar 16 of the pawl, and forces the latter

in engagement with the teeth. The ends of the cross-bar 16 of the pawl are arranged in slots 17 of one of a pair of metallic straps 18 and 19, that have their ends secured to the side faces of the standard and form guides or keepers for the jack-bar. The rack-bar is engaged by a lever 20, which is pivoted in the slot 7 of the standard 1, and is provided with a longitudinal slot 21, through which the pivot 22 passes, whereby the lever 20 is capable of a limited longitudinal movement and is adapted to engage a tooth of the rack-bar, lift the jack-bar, and be withdrawn from engagement with said tooth and brought in engagement with another tooth to again lift the jack-bar, and as the latter is elevated the spring-actuated pawl 14 engages the teeth and prevents the jack-bar dropping when the lever 20 is withdrawn from engagement with the rack-bar. The lever 20 is connected by plates 23 with an operating-lever 24, which has one end pivoted between perforated ears 25 of a plate 26, that is secured to the standard, and the 75 said plates 23 are arranged upon each side of the levers 20 and 24 and are pivotally connected thereto, and the lower pivot 27 is adapted to be adjusted in the openings 28 of the operating-lever 24 to vary the force of the 80 pull and the stroke of the operating-lever. The plates 23 are also provided with adjusting-openings 29, and they are capable of a limited movement on the operating-lever and are adapted to alternately engage a projecting 85 lug 30 and plates 31 to move the lever 20 and force it into engagement with the teeth of the rack-bar and withdraw it therefrom. The upper edge of the operating-lever is provided with notches 32, in one of which is arranged 90 the lug 30, that is adapted to be adjusted along the lever and that projects laterally from both sides of the same, and the plates 31 are arranged upon each side of the operating-lever and are provided with flanges 32* to engage the plates 23, and they are connected by a rivet 33, which is arranged in a slot 34 of the operating-lever 24 and permits the plate 31 to move freely and adjust itself to the plates 23.

The lifting-jack is provided with suitable metallic plates to protect the part from wear and strengthen the same, and it has secured to its lower end a metallic band 35, which pro-

jects below the standard and is adapted to engage the supporting-surface and prevent the standard slipping, and the upper end of the jack-bar is provided with a pivoted plate 36, that has its end 37 pointed and adapted to receive between them an axle, or to engage a piece of lumber and prevent the lumber or axle slipping from the jack.

It will readily be seen that the lifting-jack is simple and economic in construction and is adapted to be readily operated, and is capable of vehicle, lumber, and kindred uses.

Having thus described my invention, I claim—

- 15 1. The combination, in a lifting-jack, of the standard, the vertically-movable jack-bar provided with a rack, the spring-actuated pawl arranged to engage the rack, the lever 20, pivoted in the standard and provided with a longitudinal slot and capable of longitudinal movement and arranged to engage the said rack, and the operating-lever connected with the lever 20, substantially as described.
- 20 2. The combination, in a lifting-jack, of the standard, the vertically-movable jack-bar provided with a rack, the spring-actuated pawl, the slotted lever 20, pivotally mounted in the standard and capable of longitudinal movement and arranged to engage the rack-bar,

the operating-lever 24, pivoted to the standard 30 and provided with the lug 30 and the plates 31, and the connecting-plates 23, having their ends pivoted to the levers and being arranged to be alternately engaged by the lug and the plates 31, substantially as described. 35

3. The combination, in a lifting-jack, of the recessed standard, the jack-bar similarly recessed and provided with a rack, the metallic straps having their ends secured to the sides of the standard and forming keepers or guides 40 for the spring-actuated pawl, the longitudinally-slotted lever 20, capable of longitudinal movement and arranged to engage the rack, the operating-lever 24, pivoted to the plate 26, provided with notches 32 and the slot 34 45 and having the lug 30 arranged in one of the notches and the plates pivotally mounted in the slot 34, and the connecting-plates pivoted to the levers and arranged to be alternately engaged by the lug and the plates, 50 substantially as described.

In testimony that I claim the foregoing as my own I have hereto affixed my signature in presence of two witnesses.

ISAAC N. GROVES.
